Patented Sept. 8, 1964

199,112

FAUCET AERATOR

Frank N. Williams, Wadsworth, Ill., assignor to Federal-Huber Company, Chicago, Ill., a corporation of Illinois

Filed Nov. 2, 1961, Ser. No. 67,375

Term of patent 14 years

(Cl. D91—3)

Fig. 1.

Fig. 2.

Fig. 3.

Fig. 4.

Fig. 5.

FIG. 1 is a perspective view of a faucet aerator embodying my new design;

FIG. 2 is a top plan view thereof;

FIG. 3 is a bottom plan view thereof;

FIG. 4 is a side elevational view thereof; and

FIG. 5 is an enlarged partial vertical cross sectional view taken on the line 5—5 of FIG. 3.

I claim:

The ornamental design for a faucet aerator, substantially as shown.
